(57) **CLAIM**

The ornamental design for a string light, as shown and described.

DESCRIPTION

FIG. 1 is a top perspective view of a string light, showing my new design;

FIG. 2 is a bottom perspective view thereof;

FIG. 3 is a front view thereof;

FIG. 4 is a rear view thereof;

FIG. 5 is an enlarged view of its left side view thereof;

FIG. 6 is an enlarged view of its right side view thereof;

FIG. 7 is a top view thereof;

FIG. 8 is a bottom view thereof;

FIG. 9 is an enlarged perspective view thereof, taken from encircled portion 9 in FIG. 1;

FIG. 10 is an enlarged perspective view thereof, taken from encircled portion 10 in FIG. 1; and,

FIG. 11 is an enlarged perspective view thereof, taken from encircled portion 11 in FIG. 2.

The drawings include multiple symbolic breaks in the string light. The portions of the string light between the breaks that are not shown in the drawings form no part of the claimed design.

The dot-dash broken lines represent the boundary of the enlarged portions and form no part of the claimed design.
